CLOSURE DEVICE FOR CONTAINERS

Thomas E. Piazze, Mount Vernon, Ohio, assignor
to Shellmar Products Corporation, Chicago,
Ill., a corporation of Delaware

Application April 22, 1947, Serial No. 743,112

5 Claims. (Cl. 215—11)

1

The present invention has to do with closure devices for containers. More particularly, it has to do with an improved type of closure device particularly adaptable for use in conjunction with flexible disposable containers, and the provision of such a device as well as a closure and flexible disposable container combination are principal objects of the invention.

This invention is a continuation-in-part of my copending application Serial No. 668,267, filed May 8, 1946, now abandoned.

The invention has particular utility, for example, with the use of infants' flexible disposable feeding bottles made of such materials as Cellophane, rubber hydrochloride, polyethylene, and the like. Such containers are finding a ready market because of the fact that they can be kept sterile until used and also because they are disposable after a single use. In addition to this, such containers, because of their flexibility, will readily be collapsed during use, thereby preventing the creation of a vacuum therein, consequently minimizing infants' colic which is otherwise prevalent as the result of the use of conventional glass bottles.

In its broader aspects, the invention has for one of its objects the provision of a closure device for such containers comprising a cap having an extension to be inserted into the open end of a container, a flexible sealing member to fit over the extension and to hold the container end in position, and a locking member adapted to fit over the sealing member and to compress the container end into sealed engagement with the closure extension.

More specifically, it is an object of the invention to provide a container closing device for flexible disposable containers of the type embodying a tube closed at one end and having particular utility as an infant's nursing bottle, comprising in combination a cap member having an extension with spaced apart peripheral grooves therein adapted to be inserted within the open marginal end of a container, a flexible sealing member, such as a rubber ring, to fit around one of the grooves temporarily to hold the container in position, and a locking member adapted frictionally to engage the sealing member and to advance or roll it from its initial position to the other groove lockingly to hold the same and the container operatively in hermetically sealed condition with respect to the cap member.

Other objects of the invention will in part be obvious and will in part appear hereinafter.

2

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawings, in which:

Fig. 1 is an elevational view, with parts in section, of a bottle closure device and a flexible disposable container arranged in exploded alignment, illustrating a preferred embodiment of the invention and depicting the manner of assembling the same;

Fig. 2 is a view somewhat similar to Fig. 1 depicting the flexible container inserted over an extension of the cap member;

Fig. 3 is a view showing the body of the container tucked within the cap member after the sealing ring has been placed around the extension of the cap member to hold the marginal portion of the bag or container in position;

Fig. 4 shows a further stage in the assembly of the container closure device, in which a locking member is being placed in position over the sealing ring;

Fig. 5 illustrates the locking member frictionally being brought into engagement with the sealing member, the application of the locking member serving to roll the sealing member out of its initial position to its final locking position;

Fig. 6 illustrates the closure cap device holding the container in locked and hermetically sealed position by means of the locking member; and

Fig. 7 is a fragmentary sectional view of a modified form of the invention.

Referring more particularly to the drawings, there is shown in Fig. 1 a cap member 10 having an extension 11 adapted to fit within a container 12. This container preferably is of the extruded tubular type or of the seamed tubular type having a transverse seal 13 across the bottom.

The extension 11 of the cap member 10 preferably has two peripheral grooves 14 and 15. The remaining portions constituting the closure device consists of a sealing ring member 16, preferably made of natural rubber, and a locking ring 17 which is internally tapered preferably as at 18 and 19 respectively. The purpose of this type of double taper is to make this locking member operate in either direction.

In use, the extension 11 of the cap member 10 is inserted within the open end portion of the container 12 as shown in Fig. 2.

Referring now to Fig. 3, it will be seen that, during the course of assembling the bottle closure cap and container assembly, the sealing ring 16 has been placed over the marginal portion of the container 12 in such a manner that the ring 16 initially is seated in the groove 14 around the container. This helps locate the container 12 in proper position, bringing it in alignment with respect to the extension 11 of the cap member 10. As a matter of convenience, the remaining portion of the container may be tucked in the cap member as illustrated so that it is in an out of the way position.

Thereafter, in continuing the assembly of the device, the locking ring 17 is brought into position as shown in Fig. 4. It is within the contemplation of the invention to have a single taper but by having both tapers 18 and 19, it is possible to apply the locking ring in either direction.

The locking ring 17 first engages the sealing ring 16, and as it is pressed upwardly into position the sealing ring becomes flattened as it is rolled out of the groove 14 in the direction of the peripheral groove 15. The space therebetween forms a locking shoulder, or landed portion, 20. As the locking ring is advanced along the cap extension 11, it continues to roll the sealing ring 16 past the locking shoulder 20 until it becomes sealed within the annular groove 15, thereby holding the container portion in compressed engagement peripherally within the groove in an hermetically sealed position with respect to the extension 11 on the cap member 10.

In the modification shown in Fig. 7 the skirt 111 of the cap member 110 does not have a peripheral groove. However, the locking member 117 can be equipped with one or more of such grooves, as indicated generally at 115, to lock a marginal peripheral portion of a container 112 against a sealing ring 116.

The sealing ring 16 in the groove 15, compressed by the locking member 17 holds all parts in locked engagement during use.

It is within the contemplation of the invention to utilize one or more peripheral grooves in such a manner as to provide locking shoulders in conjunction with tapered counterparts on other portions of the locking device. Also, it is within the contemplation of the invention to provide the locking member 17 with a single taper as well as with grooves corresponding to those illustrated in the extension 11.

After the container is filled through the open end of the cap member 10 a nipple can be applied on the shouldered neck portion 21 and the same is ready for use.

The closure device has been described as being particularly adaptable for use in conjunction with flexible disposable containers especially useful for infants' feeding bottles, but other uses for the invention will readily occur to those skilled in other related arts.

It will thus be seen that the objects hereinbefore set forth may readily and efficiently be attained, and since certain changes may be made in the above article and different embodiments of the invention could be made without departing from its scope, it is intended that all matter contained in the above description, or shown in the accompanying drawings, shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent is:

I claim:

10. In a closure device for flexible disposable containers, a cap member having an extension with a peripheral annular groove adapted to be inserted into the open end of said container, a resilient sealing ring member adapted to fit over said extension when said extension is positioned in said container end, said ring member being adapted to hold said marginal container end thereagainst, and a rigid band-like locking member adapted to fit over said sealing member and to compress said container end into sealed engagement with said closure extension and into locked engagement with said annular groove.

2. In a closure device for flexible disposable containers, a cap member having an extension with a peripheral annular groove adapted to be inserted into the open end of the container, a resilient sealing ring member of slightly less internal diameter than the external diameter of said extension adapted to fit over said extension when said extension is positioned in the end of the container and to hold said container end thereagainst, and a locking member having an internally tapered surface, said locking member being adapted frictionally to engage said sealing member and compress it into locked engagement with said extension, thereby hermetically to seal said container therebetween.

3. The combination of a flexible disposable container with a closure device comprising a cap member having an extension adapted to be inserted into the open end of said container, a flexible sealing ring member of a size adapted to fit over said extension and to hold said marginal container end thereagainst, and a locking member having an internally tapered surface being of a size to frictionally engage said sealing member and compress it into locked engagement with said extension, whereby hermetically to seal said container therebetween.

50. 4. In a closure device for a flexible disposable container, a cap member having an extension with spaced apart peripheral grooves therein, said cap member being adapted to be inserted into the marginal end of said container, a stretchable sealing member adapted to fit around the outer one of said grooves to temporarily hold said container in position, and a locking band member having a tapered inner surface, said band member being adapted frictionally to engage said sealing member and to advance the same from its initial position to the inner one of said grooves lockingly to hold the said container in operative position with respect to said cap member.

5. In a closure device for flexible disposable containers, a cap member having an extension with spaced apart peripheral grooves therein adapted to be inserted into the open end of said container, a flexible sealing member adapted to fit the outer one of said grooves temporarily to hold said container in position, and a locking band member having a tapered internal surface adapted to fit over said sealing member and to compress said container end into sealed engagement with said closure extension and lockingly to hold the cap sealing member and locking member

in fixed position with the marginal container end therebetween.

THOMAS E. PIAZZE.
